UNITED STATES PATENT OFFICE.

HOWARD B. CARPENTER, OF PUEBLO, COLORADO.

HORIZONTAL COKE OVEN.

Application filed October 18, 1921. Serial No. 508,552.

To all whom it may concern:

Be it known that I, HOWARD BRUCE CARPENTER, a citizen of the United States, residing at Pueblo, in the county of Pueblo and State of Colorado, have invented certain new and useful Improvements in Horizontal Coke Ovens, of which the following is a specification.

This invention relates to the manufacture of coke and particularly to the construction of horizontal coke ovens, known also as horizontal chamber ovens and coking retort ovens used for the manufacture of metallurgical and other coke.

While the by-product coke ovens now in operation do produce a satisfactory grade of metallurgical or other coke, they are not universally applicable as there are only a few certain coals which can be successfully coked therein without special preparation and admixture with other coals. When a rectangular horizontal coking retort or chamber oven is filled with coal to the charging line, the coal mass contained therein often has a variable weight for each unit foot in height, due in part to the compressing weight of the coal column, and thus producing a coking mass of less density at the top than at the bottom of the oven. It is a well known fact that some coals, usually those with a high volatile matter content, when coked at high temperatures, which are necessary in order to reduce the period of time required for the complete coking process to an efficient and economical point, form in the upper part of the coking chamber and at the points where the density of the coking mass is least, more or less large quantities of a product known as "sponge". This material, which is of a very light, porous and fragile nature, is entirely unsuited for use as a fuel for metallurgical or domestic purposes, and may be classed as a waste product. Inasmuch as this product may attain the proportion of twenty-five percent of the entire oven yield, this loss is not one that may be lightly overlooked.

This tendency of some coals to form "sponge" can be lessened to some degree by admixture with a coal whose tendency is to form a very dense coke (usually a low-volatile coal) and also by lowering the temperature at which the coking process is conducted. Both of these methods are quite uneconomical, however, as in the first case such a special coal, if not entirely unavail-

able, must usually be brought from some distance, and in the second case the loss due to decreased production would be considerable.

This invention includes among its objects to produce an increased coking efficiency in the type of ovens having horizontal coking retorts or chambers, an increase in the production of a satisfactory grade of metallurgical and other coke from the various coking coals, an increase in the by-product recovery yields through the creation of a lower temperature zone in the upper portion of the coking chamber, a decrease in operating expense due to increased production by operating at high temperatures, and such other advantages and improvements in construction and operation as may be found hereinafter described and claimed.

The accompanying drawings illustrating an embodiment of my invention show the horizontal coking retort or chamber with vertical heating combustion flue arrangement, but I desire it to be understood that the said principles may also be used in connection with horizontal coking retort or chambers with horizontal combustion flues for heating or with any other heating system which may be used in connection with horizontal coking retort or chamber ovens. In the accompanying drawings is shown, for purposes of exemplification, a preferred manner in which this invention may be embodied in an installation of existing type, but without limiting the claimed invention specifically to any such illustrative instance or instances.

Figure 1 is a vertical longitudinal section through a coking retort or chamber and the regenerators below it taken on the line C—C of Fig. 2; Fig. 2 is a vertical transverse section through a battery of two ovens taken on the line A—A of Fig. 1, showing the walls forming the coking retort or chamber inclined toward the center of the chamber and the taper of the chamber extending from the points 1, 1 in the walls to the top of the chamber; Fig. 3 is a vertical transverse section through a battery of two ovens taken on the line A—A of Figure 1, showing the coking retort or chamber tapering upwardly and from the points 2, 2 in the walls of the chamber or retort to the top; Fig. 4 is a vertical transverse section through a battery of two ovens taken on the line A—A of Fig. 1, showing the walls

forming the coking retorts inclined toward the vertical plane of the retorts and the taper of the retorts extending from the points 3, 3 in the vertical walls to the top of the retort chamber; Fig. 5 is a vertical transverse section through a battery of two ovens taken on the line A—A of Fig. 1, showing the coking retort tapering upwardly and the taper extending completely from the bottom 10 to the top of the chamber; and Fig. 6 is a horizontal section through three combustion chambers or heating flues and two coking chambers taken on the line B—B of Fig. 2, showing the taper of the coking 15 chamber from the coke side to the pusher side of the battery, but also showing the upward tapering of the coking retort from the points 1, 1 in Fig. 2 to the top of the chamber. Similar sections taken on this 20 line through Figs. 3, 4 and 5 would be identical with this.

Fig. 2 showing the inclination of the walls 8 from the points 1, 1 in the walls to the top of the coking retort or chamber 10 is intended 25 to be used for a coal which has but a slight tendency to form "sponge" during the coking process. In the operation of a coking retort or chamber of this design, the walls from the points 1, 1 to the top would be kept at a lower temperature than that portion of the walls below these points, due to the decreased amount of coal contained in this portion of the oven; and hence the amount of "sponge" is reduced correspondingly 30 with the reduction in temperature. Also in a coking retort or chamber of this type the amount of "sponge" produced will be still further reduced by the fact that the direction of coking is at right angles to the heating walls of the combustion flues 9, hence in the upper portion of this chamber the bubbling of the fusion which is the cause 35 of the sponge production will be hindered to a considerable degree by the downward coking effect.

Fig. 3 shows the coking retort or chamber tapering upward from the points 2, 2 to the top of the chamber and is intended for use in connection with a coal which has a greater 40 tendency to form sponge than that which would be used in connection with Fig. 2 described above. In this case the same elements enter into the prevention of sponge as are outlined in the preceding paragraph.

Fig. 4 shows the coking retort or chamber 45 tapering upward from the points 3, 3 to the top of the chamber and is intended for a coal which has a tendency to form a great amount of sponge, the angle of deflection 50 of the walls to be determined as the characteristics of the coal may require.

Fig. 5 shows the coking retort or chamber tapering upward from the bottom of the chamber completely to the top and is intended 55 for use in connection with a coal which has a tendency to form a very great amount of sponge during the coking process, the angle of the taper of the coking chamber to be determined by the characteristics 60 of the coal to be used.

My invention as hereinafter claimed may, of course, be embodied in various ways and forms other than the embodiment which has here been used as an illustrative instance. Those features of my invention exemplified 65 in the above description and which relate particularly to the employment of coking retorts of a horizontal coking oven having walls inclined toward the central plane of the retorts at the top for a coal which has a 70 tendency to form sponge during the coking process, may be of such an angle as best adapted for the coal to be used, and the deflection may start at any point or points in the perpendicular walls of the chamber 75 and extend upward to any point or points in the walls or to the top of the coking retort.

I claim:

A coke oven structure comprising alternate coking retorts and vertical combustion flues, the walls of the lower portions of both the retorts and the combustion flues being parallel, and in each retort the upper portion of each wall common to the retort and the contiguous flues being inclined toward the middle vertical plane of the retort, and away from the said plane of said contiguous combustion flues, so that the lower portion of both retorts and combustion flues is a parallelepipedon, and the upper portion, a trapezoidal prism, the upper side of said prism being broader than the lower in the combustion flues and narrower in the retorts.

In testimony whereof I affix my signature.

HOWARD B. CARPENTER,
